BOWDEN WASHINGTON, OF NEW YORK, AND WILSON AULL, JR., OF ASTORIA, NEW YORK, ASSIGNORS TO REMOTROLE CORPORATION, A CORPORATION OF NEW YORK

CONTROL SYSTEM FOR RADIORECEIVERS

Application filed June 25, 1927. Serial No. 201,393.

One object of our invention is to produce a system by means of which any modern radio receiver may be controlled from a distance both as to received frequencies and as to 5 sensitivity over any wavelength or frequency band desired.

Another object is to provide a system in which the control unit is readily portable.

Another object is to provide a simple single 10 control arrangement for multi-stage so-called vacuum tube or electron relay amplification.

Another object is to provide a high power receiver of single frequency response which can be made to respond to a wide band of 15 frequencies by means of a control station having a single frequency-control element located at any convenient point and may also have its out-put amplitude controlled at or near the same point.

20 By means of our invention practically any modern radio receiver from the high frequency amateur type to the low frequency Navy type may be converted to take, for instance, the broadcast frequency band, or any 25 other band, and control it from a distance without intervening physical means, such as wires, cables, etc.

In our invention the signal is picked up by 30 a portable control box which may preferably contain a tunable regenerative detector having a coil, loop or capacity input. The output of this detector is associated with the input of a stage of audio frequency amplification. The output of the latter serves to 35 modulate an oscillator having a fixed frequency output. This oscillator has in its output circuit coupling means which may be either electro-static or electro-magnetic, said coupling means coacting with other coupling 40 means associated with the input of a frequency changer whose output is in turn associated with the input of a receiver tuned to a chosen wavelength or with a fixed frequency receiver designed especially to coact with the 45 other units of our invention. The system is susceptible of embodiment in various ways for different purposes.

Referring to the drawings:

Fig. 1 is a diagrammatic drawing of the 50 system as a whole.

Fig. 2 is a schematic wiring diagram of one form of frequency changer.

Fig. 3 is a schematic wiring diagram of one form of control unit.

Fig. 4 is a schematic wiring diagram of 55 another form of frequency changer.

The control box 10 has a signal pick-up 60 coil or loop 11, a frequency adjuster 12, a gain control 13 and an output loop 14. The frequency changer 15 has an input pick-up 65 loop 16 and is connected to the receiver 17 loop 18 and is connected to the receiver 17 which has an output device 19.

In operation the coil antenna 11 and its 70 associated circuit is adjusted by the condenser 12 to be resonant with the frequency it is 65 desired to receive. Associated with this circuit is the regenerative detector 20 with its regeneration control 21. The audio frequency output of the detector 20 by means of the vacuum tube 22 and the transformer 23 75 is further amplified and serves in any suitable manner to modulate the oscillator 24 having an output device 14. The frequency of this oscillator 24 may be permanently adjusted by the adjustable condenser 25. The amplitude of the modulation of the oscillator 24 80 may be varied by adjusting the plate voltage of the amplifier 22 by means of the high variable resistance 26 and by varying the sensitivity of the detector 20 by means of the 85 adjustable feed back control 21. For convenience it may be preferable to operate these two adjustments by means of one manual control as indicated by the dotted line 13', Fig. 3, and the single knob 13, Fig. 1.

If a frequency changer of the type shown in Fig. 2 is used the further operation of the system is as follows:

Let us assume that the receiver 17 is either 90 built or adjusted to respond to 530 kilocycles. Then for example the modulated oscillator 24 may be operated at 30,000 kilocycles while the oscillating detector 28 may be adjusted to a frequency of 30,530 kilocycles, then by 95 means of the usual heterodyne action the output or anode circuit of the oscillator detector 28 will have impressed upon it a frequency of 530 kilocycles which we have assumed to be the response frequency of the receiver 17. The numerical values taken are purely illus- 100

trative. It will be readily seen that almost any values if they are properly correlated may be used.

If a frequency changer of the type schematically illustrated in Fig. 4 is used the operation is somewhat different though the results attained are similar. In this case the oscillator 24 may be adjusted to any desired frequency and the circuit of the regenerative detector 30 adjusted for maximum sensitivity for the same frequency. The output of the detector 30 modulates in any suitable manner the oscillator 31. The frequency of the modulated output of the oscillator 31 may be permanently set or adjusted by the adjustable condenser 32 to whatever maximum response frequency is chosen for the receiver 17.

The receiver 17 may have in its output circuit any suitable indicating device such as 20 the loud speaker 18.

In summation the invention consists in selecting and amplifying the desired signal at the control unit and modulating and retransmitting at a fixed frequency the modulations 25 of the desired signal at any chosen frequency regardless of the frequency of the incoming wave, retransmitting from the control unit to a frequency changer associated with any desired receiver, said frequency changer 30 changing the carrier frequency of transfer to the chosen resonant frequency of said receiver.

It should be understood that the apparatus 35 may be sold complete or the control unit and frequency changer may be sold to be used with an ordinary receiver. A single control unit may be used to excite a number of receivers or a single receiver might be capable of being excited by a number of control units. The 40 control unit being relatively small is readily portable and the remainder of the system which may be quite large and cumbersome may be concealed in a closet or other out of the way place. Ordinarily, of course, the loud 45 speaker would be located at or near the place where its output is desired and usually near the control unit. The receiver may be turned on and off by a switch operator 33 or by a switch at or near the loud speaker as in our 50 application #198,470, filed June 13, 1927.

It will be understood that the control unit 55 will require only a small amount of anode and cathode power and may be energized by small self-contained dry batteries. The frequency changer and the receiver may be operated by the usual dry cells, storage batteries, or house current, etc.

We do not wish to limit ourselves to the exact embodiments described except in so far 60 as we are limited in the following claims.

We claim:

1. In a radio receiving system the combination of a remote control station having a receiving member and a radiating member, means connected with said receiving member

for selecting and amplifying the desired signal, an oscillator of fixed frequency furnishing energy to said radiating member and means for modulating the amplitude of the generated oscillations of said oscillator in accordance with the modulation of said selected signal, together with a radio receiver of fixed frequency response located at a short distance from the control station and having means for amplification and detection and a frequency converter connected with the radio receiver having pick-up means for receiving the signals radiated for the control station and converting them to the response frequency of the receiver.

2. In a radio receiving system the combination of a portable control station having a receiving member, means connected with said receiving member for selecting and amplifying the desired signal, an oscillator of fixed frequency and means for modulating said oscillator in accordance with the modulation of said selected signal, together with a radio receiver of fixed frequency response and located at a short distance from the control station and having means for amplification and detection, a frequency converter connected with said latter means whose output frequency is adjusted to the resonant frequency of said receiver, means for coupling the output of said oscillator with the input of said frequency converter and means at the portable control station for controlling the volume of the output of the receiver.

3. In a radio receiving system the combination of a control station having a receiving antenna, a radiating member, vacuum tube means connected with said receiving member for selecting and amplifying the desired signal, a vacuum tube oscillator of fixed frequency connected with said radiating member, means for modulating said oscillator in accordance with the modulation of said selected signal, a source of power for the control station together with a vacuum tube radio receiver at a short distance from the control station having vacuum tube means for amplification and detection and a frequency converter connected with said latter means whose output frequency is adjusted to the resonant frequency of said receiver and also modulated by said oscillator and a separate source of power for said receiver.

4. The method of household broadcast reception which comprises collecting and selecting signals of a desired frequency within a broadcast range of frequencies, demodulating the selected signals and amplifying the same, generating a fixed frequency carrier wave and modulating the carrier wave by the amplified signals, radiating the modulated carrier wave, absorbing and selecting the radiated wave at a distance, demodulating the absorbed and selected wave, generating a local fixed frequency wave, modulating

said local fixed frequency wave by the de-modulated absorbed wave, impressing the modulated output upon an ordinary radio receiver at a frequency outside the broadcast range and controlling the volume of the output by varying the strength of the first de-modulated signal.

5. The method of household broadcast reception which comprises collecting and selecting signals of a desired frequency, demodulating the selected signals and amplifying the same, generating a fixed frequency carrier wave and modulating the carrier wave by the amplified signals, radiating the modulated carrier wave, absorbing and selecting the radiated wave at a distance, demodulating the absorbed and selected wave, generating a local fixed frequency wave, modulating said local fixed frequency wave by the de-modulated absorbed wave, impressing the modulated output upon a radio receiver having radio and audio amplifying stages and controlling the volume of the output by varying the strength of the first demodulated signal.

6. The method of household broadcast reception which comprises collecting and selecting signals of a desired frequency within a broadcast range of frequencies, demodulating the selected signals and amplifying the same, generating a fixed frequency carrier wave and modulating the carrier wave by the amplified signals, radiating the modulated carrier wave, absorbing and selecting the radiated wave at a distance, demodulating the absorbed and selected wave, generating a local fixed frequency wave, modulating said local fixed frequency wave by the demodulated absorbed wave and impressing the modulated output upon an ordinary radio receiver at a frequency outside the broadcast range.

BOWDEN WASHINGTON.
